UNITED STATES PATENT OFFICE.

JAMES CHAMBLESS, OF JASPER, ALABAMA, ASSIGNOR OF ONE-HALF TO ALBERT RUSSELL, OF JASPER, ALABAMA.

STEAM-ENGINE VALVE AND REVERSING MEANS THEREFOR.

1,387,468.

Specification of Letters Patent. Patented Aug. 16, 1921.

Application filed March 15, 1919. Serial No. 282,958.

To all whom it may concern:

Be it known that I, JAMES CHAMBLESS, a citizen of the United States, residing at Jasper, in the county of Walker and State 5 of Alabama, have invented certain new and useful Improvements in Steam-Engine Valves and Reversing Means Therefor, of which the following is a specification.

This invention has to do with improvements in steam engine valves.

The valve which is here involved is of the revolving type and is designed to take the place of the conventional slide-valve operated by an eccentric, the dispensing with 15 which in this construction eliminates many disadvantages found in the use of slide-valves especially in high speed engines or those capable of developing high speed. For instance, it is well known that the reciprocating action of the slide-valve at high 20 speed becomes more or less jerky and this results in the course of time to the loosening up of many of the parts and connections which for this reason require constant attention. On the other hand, in my type of 25 construction the continuity of revolving of the valve makes for smoothness of action, less wear and tear, and may be accompanied by increase of speed and power.

These and such other objects and advantages as may hereinafter appear are attained by the novel construction, combination and arrangement of parts to be hereinafter specifically described and claimed. Reference 30 will now be had to the accompanying drawings forming a part of this specification, wherein:

Figure 1 is a plan view of a device constructed in accordance with this invention;

Fig. 2 is a sectional view on the plane indicated by the line 11—11 of Fig. 1;

Figs. 3 and 4 are sectional views of a modified form of my valve arrangement; and

Fig. 5 is a perspective view of the valve member used in the type shown in Figs. 3 and 4.

Throughout the following detail description and on the several figures of the drawings, similar parts are referred to by like reference characters.

In the drawings, I have illustrated one embodiment of my invention, but I desire it to be understood that I do not wish to be limited to the specific arrangement in which

the steam chest is directly mounted upon or in conjunction with the crank shaft of the engine. With this in mind at 32 is indicated a steam chest surrounding the engine crank shaft 33, the body of said chest being 60 preferably composed of separable sections bolted together in the position shown in the drawing. The steam chest 32 communicates with the cylinder 34 through the conduits 35, the steam chest entrances to which open 65 through the wall of the chest adjacent to the shaft 33 and as indicated at 36 in Fig. 1 of the drawing. Within the chest is mounted a valve 37, which valve controls the admission and exhaust of the steam by reason 70 of its special construction hereinafter referred to. The exhaust takes place through the passages 38 and the steam is supplied to the steam chest through the conduit 39. A reversing lever 40 is employed to shift 75 the valve 37 relatively about its axis when it is desired to reverse the engine. For this purpose the shaft 33 carries a sleeve 41 to which the valve 37 is fixed. This sleeve is provided with a spiral slot through which 80 a key member 42 projects into engagement with a grooved collar 43. Thus when the reversing lever 40 is shifted laterally into positions shown by dotted lines in Figs. 1 and 2 the sleeve 41 has imparted thereto partial rotation which carries the valve in like manner and causes a movement of the same relative to the ports in the steam chest.

Referring to Figs. 3, 4 and 5, it will be noted that the valve body is solid, and is 90 formed with a covering portion 12^b which is adapted to coöperate with a short passage 10^a in the wall of the steam chest at one side of each of the cylinder supply passages 7 and 8. These short passages 10^a have a 95 common exhaust outlet indicated at 10^c in Fig. 3. Thus with the formation of the valve with the covering portion 12^b for closing the ports 10^b, steam will enter the chest through the passage 14 and passes into one 100 of the passages 7 or 8, depending upon which is uncovered at the time by the valve. The other of said passages at this time is placed in communication with its adjacent port 10^b by a chamber 12^a formed in the valve. Continued movement of the valve will change 105 the supply of steam to the opposite end of the cylinder as the other exhaust port is covered and the supply of steam is permitted to pass into the other end of the cylinder 110

through this chamber passage 12^a of the valve.

It will be understood that it is within the purview of this invention to utilize air or other like pressure as an actuating medium instead of steam, and I do not therefore wish to be limited in this respect.

Having thus described my invention, what I claim as new and desire to secure by Letters Patent is:

In a steam engine, a cylinder, a steam chest therefor, an axle journaled in a wall of said steam chest and having an end projecting thereinto, a valve mounted upon said end and bearing against said wall, a steam

supply port opening through said wall at each side of said axle and leading to the opposite ends of said cylinder, and a separate exhaust port arranged adjacent to each of the supply ports in said wall and having a common outlet, said valve comprising a chamber adapted during rotation of said valve to establish communication successively between each pair of supply and exhaust ports while cutting off said ports from communication with said steam chest, and a portion adapted to simultaneously close the other exhaust port.

In testimony whereof I affix my signature.

JAMES CHAMBLESS.
